Specification for Design.

Patented Mar. 28, 1922.

Application filed August 29, 1921. Serial No. 496,715. Term of patent 14 years.

To all whom it may concern:

Be it known that I, DANIEL J. MURNANE, Jr., a citizen of the United States, and residing at Detroit, county of Wayne, and State of Michigan, have invented a new, original, and ornamental Design for an Exterior Member of a Store-Front Corner Bar, of which the following is a specification, reference being had to the accompanying drawing, forming a part hereof.

Referring to the accompanying drawing, Figure 1 is a perspective view of the exterior member of a store-front corner bar of my improved design; and Figure 2 is an end view thereof.

I claim:

The ornamental design for an exterior member of a store-front corner-bar, as shown.
